MINIATURE GOLF BALL DELIVERING AND
REGISTERING MEANS

Wilburn Lee McCall, Marion, S. C.

Application July 14, 1931. Serial No. 550,743

1 Claim. (Cl. 235—91)

This invention relates to registers, and has for one of its objects to provide a novel apparatus of this character which shall be adapted to register the number of golf balls issued in the course of a day or fraction thereof at a miniature golf course, to the end that, since each player is charged the same fee and uses but one ball to complete the course, the sum taken in during the day or any fraction thereof may be easily and quickly computed.

The invention has for a further object to provide an apparatus of the character stated which shall embody a container for the golf balls, means operable to deliver the balls one at a time from the container for issuance to the players, and means adapted to register each ball delivered from the container.

The invention has for a further object to provide an apparatus of the character stated where 20 in the container shall be adapted to have the golf balls automatically delivered thereto from the last hole of the course.

With the foregoing and other objects in view, the nature of which will appear as the description proceeds, the invention consists in the construction, combination and arrangement of parts hereinafter fully described and claimed, and illustrated in the accompanying drawings, where 25 in:—

30 Figure 1 is a sectional view taken on a plane extending vertically and longitudinally through the apparatus.

Figure 2 is a sectional view taken on a plane extending horizontally through the apparatus, 35 the plane of the section being indicated by the line 2—2 of Figure 1.

Figure 3 is a sectional view taken on the vertical plane indicated by the line 3—3 of Figure 2.

40 Figure 4 is a detail sectional view taken on the vertical plane indicated by the line 4—4 of Figure 2.

Figure 5 is a detail sectional view on an enlarged scale taken on the vertical plane indicated by the line 5—5 of Figure 2, and

Figure 6 is a detail sectional view on an enlarged scale taken on the vertical plane indicated by the line 6—6 of Figure 2.

The apparatus, which will be preferably located at or close to the entrance of a miniature golf course, comprises a casing 1 which includes a bottom wall 2, top wall 3, side walls 4, front wall 5 and rear wall 6. A container 7 for the golf balls 8 is located within the casing 1, and comprises an upright tube 9, a tube 10

inclining downwardly from one side wall 4 of the casing, and a tube 11 extending downwardly from the lower end of the tube 10 to the lower end of the tube 9. The upper end of the tube 10 extends outwardly of the casing 1 to 60 permit the golf balls to be placed in the container 7. A cup 12 located outwardly of the casing 1 and communicating by way of a tube 13 with the tube 10, provides means through the medium of which the golf balls may be placed 65 in the container 7. The cup 12 constitutes the last hole of the course, and is carried by a support 14 located above the normal surface of the course. An inclined path 15 extends from such surface to the support. The player must, 70 in order to make the last hole of the course, drive a golf ball up the path 15 over the support 14 and into the cup 12, resulting in the automatic return of the golf ball to the container 7.

The golf balls 8 are raised from the lower to the upper end of the upright tube 9 by means which comprises an endless belt 16 arranged in upright position along side the tube, and fingers 17 carried by the belt and extending into the tube. The tube 9 is provided in a side thereof with a longitudinally extending slot 18 through which the fingers 17 extend into the tube. A tube 19 extends downwardly from the upper end of the tube 9 to a trough 20 located at the 85 outer side of and secured to the front wall 5 of the casing 1. The raising means carries the golf balls 8 from the upper end of the tube 9 into the tube 19 which later delivers them to the trough 20 from which they may be removed 90 for issuance to the players.

The belt 16 is mounted on pulleys 21 and 22 which are fixed to shafts 23 and 24, respectively. The shaft 23 which is located in the lower end portion of the casing 1, is journaled in a bearing 25 secured to one side wall 4 of the casing. The shaft 24 which is located in the upper end portion of the casing 1 is journaled in a bearing 26 secured to said casing wall and has fixed thereto a ratchet wheel 27. A ratchet bar 28 rests upon the ratchet wheel 27 and passes through the rear wall 6 of the casing 1. A lever 29 pivoted, as at 30, to the rear wall 6, is connected, at 31, to the rear end of the ratchet bar 28 and provides means by which the ratchet bar may be reciprocated to impart turning movement in one direction to the ratchet wheel 27. The turning of the ratchet wheel 27 moves the belt 16 in such manner as to cause the fingers 17 to move the golf balls 8 upwardly in 110

the tube 9 and deliver them to the tube 19 from which they pass into the trough 20.

Means for registering the number of golf balls 8 delivered to the trough 20, comprises a numbered strip 32 which is rolled upon a spring roller 33. The roller 33 is similar to a spring shade roller, and is mounted in brackets 34 located within the casing 1 and secured to the front wall 5 thereof. The roller 33 is located 10 close to the top wall 3 of the casing, and located below the roller and parallel to the top wall 3 is a support 35 over which the numbered strip 32 moves as it is drawn from the roller 33. The support 35 is mounted on brackets 36, 15 and one end extends from the front wall 5 to a point close to the rear wall 6 of the casing 1, the rear end of the support terminating short of the rear wall to permit the numbered strip to move downwardly past said end thereof as it 20 is drawn from the roller 33. The strip 32 is numbered from one to one hundred, and as it is drawn from the roller 33 the numbers thereof pass successively below a window 37 in the top wall 3 of the casing 1, the number appearing 25 below the window indicating the number of balls delivered to the trough 20.

A shaft 38 journaled in bearings 38a and located below the support 35, has secured thereto one end of the numbered strip 32, and is turned 30 to withdraw the numbered strip from the roller 33. A shaft 39 journaled in bearings 40, is located above the shaft 38 and is connected thereto by gears 38b and 38c. A lever 41 is located within the casing 1 above the shafts 26 and 39, 35 is mounted at a point between its ends for rocking movement about a horizontal pivot 42 which is secured to the rear wall 6 of the casing. The lever 41 is provided between its ends with a downwardly directed arm 43 through the medium of which it is connected to the pivot 42, and is provided at one end with a downwardly 40 directed arm 44 and at its other end with a forwardly directed arm 45.

The arm 44 is engaged with a four lobed cam 45 46 fixed to the shaft 24, and the arm 45 has pivoted thereto a pawl 47 which engages a ratchet wheel 48 fixed to the shaft 39. The lever 41, the cam 46, pawl 47, ratchet wheel 48, gears 38b and 38c, and shaft 38 provide means 50 through the medium of which a portion of the strip is drawn or unwound from the roller 33 each time the golf ball elevating means is actuated to deliver a ball to the trough 20, the length of the strip unwound from the roller being sufficient to register one of the numbers of the strip with the window 37, and the number registered with the window indicating the number of balls issued to the players. The means for delivering the balls to the trough 20, and the means for 55 registering the number of balls delivered to the trough, are actuated through the medium of the hand lever 29. The lever 29 normally occupies an upwardly and rearwardly inclined position with respect to the rear wall 6 of the casing 1, and it is moved forwardly from this position to 60 effect the actuation of the ball delivering and ball registering means. After each actuation of these means, the arm 44 of the lever 41 engages between a pair of the lobes of the cam 46 and holds the ball delivering means against reverse 65 turning movement while the lever 29 is being returned to its normal position. The lever 41 is operated by gravity to cause its arm 44 to move between a pair of the lobes 26, and during this 70 actuation thereof the pawl 47 is moved rear- 75

wardly with respect to the ratchet wheel 48 so as to engage another tooth of the ratchet wheel.

With the arm 44 located between a pair of the lobes of the cam 46 and with the pawl 47 engaged with another tooth of the ratchet wheel 48, the ball delivering and the ball registering means are set for further actuation when the lever 29 is again moved forwardly. The shaft 38 is held against retrograde rotation by a pawl 49 pivoted to the bearing 40 and engaging 85 a ratchet wheel 50 fixed to the shaft 39.

A money drawer 51 is slidably mounted on guides 52 for movement into and out of the casing 1 through the front wall 5 of the casing. The inward movement of the drawer 51 is limited by a stop 53 mounted upon the guides 52 for contact by the rear wall of the drawer. A rod 54 secured to the bottom of the drawer 51 and slidably extending through the stop 53, and a pawl 55 secured to the stop and engaging in a notch 56 in the rod, provide means for releasably securing the drawer in closed position. The pawl 55 comprises pivotally connected sections 55a and 55b, the section 55a being pivoted, as at 57, to the stop 53, and the section 55b engaging in the notch 56 of the rod 54. A spring 58 carried by the pawl section 55b and contacting with the pawl section 55a normally holds the pawl sections in alignment to the end that the pawl will when engaged with the notch 56 100 of the rod 54 hold the drawer 51 against opening movement. When the pawl sections 55a and 55b are rocked upwardly on their pivot 59, the pawl releases the drawer 51 for movement into opened position. A coil spring 60 sleeved on the 110 rod 54 and bearing at its ends against the stop 53 and a lug 61 secured to the bottom of the drawer, is compressed during the closing movement of the drawer, and functions when the drawer is released to move the drawer into 115 opened position.

An arm 62 carried by and angularly related to the lever arm 43, and a link 63 connected to the arm 62 and to the pawl section 55a, provide means for retracting the pawl 55 each time 120 the golf ball delivering means and the golf ball registering means are actuated, the retraction of the pawl freeing the drawer 51 for movement into opened position. A bell 64 is sounded each time the drawer 51 is opened, the bell consisting 125 of a gong 65 secured to a block 66 on the bottom of the drawer 51, a hammer 67 pivoted to the block, and a spring 68 secured to the block and hammer. A stop 69 carried by one of the guides 52 trips the hammer 67 against the tension of the spring 68 during the opening movement of the drawer 51, with the result that the bell will be sounded.

In practice, the container 7 is supplied with golf balls by inserting them into the container 135 by way of the tube 12. While the container 7 is being supplied with the golf balls, the lever 29 is operated to carry the balls into the upright tube 9 of the container. The pawls 47 and 49 are held out of engagement with their ratchet 140 wheels 48 and 50, respectively, during this actuation of the lever 29. On the retraction of the pawls 47 and 49, the spring roller 33 is freed for rewinding thereon any unwound portion of the numbered strip 32. To permit of access to 145 the pawls 47 and 49, the top wall 3 of the casing 1 is provided with a door 70 which carries the window 37, which may be hinged or secured in any other suitable manner to the casing wall 3, and which may be provided with a lock, not 150

shown, for securing it in closed position. After supplying the container 7 with golf balls, and returning the pawls 47 and 49 into engagement with the ratchet wheels 48 and 50, the apparatus 5 is in condition for operation to deliver the balls one at a time for issuance to the players and to register the balls as they are delivered.

To effect the delivery of a ball to the trough 20 from which it is taken for issuance to a 10 player, the lever 29 is moved forwardly. This causes the fingers 17 of the belt 16 to move upwardly in the tube 9 and move a ball from this tube into the tube 19 which latter directs the ball into the trough 20. Simultaneously 15 with the delivery of a ball to the trough 20 the strip 32 is unrolled from the roller 33 to register one of its numbers with the window 37, and the pawl 55 is retracted to free the drawer 51 for movement into opened position. The drawer 20 51 after being closed will be automatically locked in closed position by the pawl 55 and cannot be again opened until the lever 29 is again moved forwardly to deliver another ball to the trough 20 and to actuate the strip 32 to register another 25 of its numbers with the window 37.

From the foregoing description, taken in connection with the accompanying drawings, it should be apparent that the apparatus will when actuated deliver the golf balls one at a time, and 30 will register the number of golf balls delivered in the course of a day or fraction thereof, that the number of golf balls delivered during the whole or any part of the day will be indicated by the number appearing below the window 37, 35 and that from this number may be calculated

the total receipts of the day or fraction thereof. It will also be understood that since the cup 12 constitutes the last hole of the course, the golf balls will be automatically returned to their container as the players complete the game.

While I have described the principle of the invention, together with the structure which I now consider the preferred embodiment thereof, it is to be understood that the structure shown is merely illustrative and that such changes may be made, when desired, as fall within the scope of the invention as claimed.

What is claimed is:—

A golf ball register, comprising a casing, an upright tube in the casing and provided in a side thereof with a vertical slot, means for delivering the balls to the lower end of the tube, an upright endless belt having fingers adapted to extend into the tube through the slot of the latter, means supporting the belt for operation to raise the balls in the tube, means for conveying the balls from the upper end of the tube to a point outside the casing, means operable to register the number of balls delivered from the casing, and means for simultaneously operating the ball raising and ball registering means, said latter means comprising a toothed wheel carried by the ball delivering means, means operated by said wheel for advancing the registering means, a rock lever carried by the casing, and a toothed bar connected to the lever and engaging the wheel for rotation thereof upon rocking of the lever in one direction.
